WIREWORKING MACHINE

Albert M. Bank and Alexander Nicholas, Jersey City, N. J., assignors, by mesne assignments, to Super Sagless Spring Company, Jersey City, N. J., a partnership comprising Albert M. Bank and Silvia Bank

Application August 16, 1941, Serial No. 407,146

27 Claims. (Cl. 140—71)

This invention relates to wire working machines. It is particularly directed to a machine for making zigzag shaped wire springs for upholstered chair seats and chair backs, and the like articles.

An object of this invention is to provide a machine of the character described for making springs of the character described, having predetermined length and predetermined number of turns, means being further provided to adjust the length of the springs and the number of turns in each spring.

A further object of this invention is to provide in a machine of the character described, means to vary the width of the turns so that in each spring the width of the turns decreases from the outer ends towards the middle.

Yet another object of this invention is to provide in a machine of the character described, means for varying the distances between the arms of each turn of the spring.

Yet another object of this invention is to provide a machine of the character described for making zigzag springs in predetermined lengths, and means for depositing the pieces of spring one on top of the other, as the springs are cut off.

Yet another object of this invention is to provide a machine of the character described, in which the lengths of the springs may be adjusted without adjusting the cutoff mechanism.

Yet a further object of this invention is to provide a machine of the character described for making a zigzag spring arched longitudinally.

Still a further object of this invention is to provide a machine of the character described, having means for feeding wire from a roll or other supply of wire, twisting the wire back and forth to produce a zigzag, arching the spring longitudinally and cutting off the spring in predetermined similar lengths and depositing the springs one on top of the other, all of said means operating in synchronization from a common power supply.

A still further object of this invention is to provide a strong, durable and compact machine of the character described, which shall be relatively inexpensive to manufacture, smooth, positive and economical in operation, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described,

and of which the scope of application will be indicated in the following claims.

In the accompanying drawings, in which is shown one of the various possible illustrative embodiments of this invention,

Fig. 1 is a front elevational view of a machine embodying the invention;

Fig. 2 is a rear elevational view of said machine;

Fig. 3 is a top plan view of said machine;

Fig. 4 is an enlarged cross-sectional view taken on line 4—4 of Fig. 1;

Fig. 5 is a cross-sectional view taken on line 5—5 of Fig. 4;

Fig. 6 is an enlarged cross-sectional view taken on line 6—6 of Fig. 2, illustrating the cutting off mechanism;

Fig. 7 is a cross-sectional view taken on line 7—7 of Fig. 6;

Fig. 8 is a side view of a portion of the structure shown in Fig. 7 taken in the plane indicated by numerals 8—8 of Fig. 7;

Fig. 9 is a partial cross-sectional view taken on line 9—9 of Fig. 7;

Fig. 10 is an enlarged view taken on line 10—10 of Fig. 3;

Fig. 11 is a view similar to Fig. 10, but showing another position of the parts;

Fig. 12 is a cross-sectional view taken on line 12—12 of Fig. 3;

Fig. 13 is an enlarged top plan view of the mechanism for holding the spring during the cutting off operation;

Fig. 14 is a cross-sectional view taken on line 14—14 of Fig. 13;

Fig. 15 is a cross-sectional view taken on line 15—15 of Fig. 13;

Fig. 16 is a view similar to Fig. 15, showing the mechanism opened up to permit the cut length of spring to drop;

Fig. 17 is a cross-sectional view taken on line 17—17 of Fig. 3;

Fig. 18 is a partial top plan view of the structure shown in Fig. 17;

Fig. 19 is a cross-sectional view taken on line 19—19 of Fig. 17;

Fig. 20 is a top plan view similar to Fig. 18, but showing the position of the parts after one of the pins around which the wire is twisted, has been depressed;

Fig. 21 is a view similar to Fig. 20, and showing the parts in another position;

Fig. 22 is a view similar to Fig. 20, but showing the position of the parts with the pin bearing blocks separated;

Fig. 23 is a top plan view of a length of spring made on the improved machine; and

Fig. 24 is a side elevational view thereof.

Referring now in detail to the drawings, 10 designates a machine embodying the invention for making lengths or pieces 11 of spring, illustrated in Figs. 23 and 24 of the drawings. Spring 11 as shown in the drawings is zigzag shaped, and the turns thereof decrease in width and in distance between the arms of the turns, from the outer ends of the spring towards the middle. Furthermore, the spring is arched longitudinally.

It will be noted furthermore that the end arms 12 and 12a of the spring point to the same side of the spring. The end turns of the spring 11 may be bent back inwardly beneath the arch of the spring and may be inserted into brackets fixed to seat or back frames in the manner disclosed in application of Albert M. Bank, Serial No. 362, 379, filed October 23, 1940. By having the end arms 12 pointing to the same side of the spring, the end U-shaped turns may be inserted into the brackets by moving said end turns in the same direction, thus facilitating mounting the spring on the frame.

The zigzag making mechanism

The machine 10 comprises a frame, base or support 15. The support 15 includes a horizontal table top 16, from which there extends downwardly a front wall 17 and a rear wall 18. The walls 17 and 18 are formed with aligned bearing openings 19 and 20, for the purpose hereinafter appearing.

Table 16 is furthermore formed with vertical through openings 21 and 22, the purpose of which will be hereinafter explained. At one end of table 16 are a pair of aligned horizontal bearings 24, disposed parallel to the plane of the axes of openings 21 and 22.

Fixed to the top of table 16 is a bracket 25 having parallel vertical legs 26 formed with feet 27 contacting the top of table 16, and bolted or screwed thereto, as at 28. Interconnecting the vertical legs 26 is a horizontal top wall 30 formed with a horizontal through opening 31 disposed in the plane of the axes of the openings 21 and 22.

It will be noted that bracket 25 is located between openings 21 and 22. The front end or mouth of opening 31 is conical, as at 33. A piece of wire W from any suitable roll or supply of wire, passes forwardly through the opening 31, in the direction of the arrow shown in Fig. 4, and through the mouth of said opening.

Extending upwardly from wall 30 is a vertical bearing 34 disposed in alignment with, but spaced rearwardly from opening 22. On wall 30 is a horizontal elongated bearing 36 extending from front to rear, and disposed parallel to and spaced from the plane of the axes of openings 21 and 22. Wall 30 is furthermore formed on one side thereof, with an offset arm 37 projecting toward the end of table 16 which has the bearings 24, and formed with a bearing opening 38, parallel to bearing 36.

Rotatably mounted within the bearing opening 22, and supported by table 16, is a rotary or oscillating member or head 40 formed with a sleeve 41 projecting down through opening 22 and below the table 16. Above sleeve 41 is an enlarged hub 42 contacting the top of table 16. Above the hub 42 is an enlarged cylindrical portion 43 formed at the top thereof with a diametric groove 44. The rotary head 40 is formed with an axial

through opening 46, communicating with bottom of groove 44.

Fixed to the lower end of sleeve 41 is a collar 45 disposed on the underside of table 16. Fixed to table 16, as by screws 47, is an annular bearing members 48, in which the lower end of hub portion 42 is journaled. Fixed to the hub 42 and disposed between bearing 48 and the cylindrical portion 43 is a gear 49, for the purpose hereinafter appearing.

Slidably mounted in groove 44 are a pair of similar, keyed, symmetrically disposed blocks 50 and 51 formed with horizontal longitudinal inwardly extending sockets 50a and 51a, and also with vertical cylindrical sockets or openings 50b and 51b, and with vertical slots 50c and 51c communicating with vertical openings 50b and 51b respectively.

Attached to opposite sides of the cylindrical portion 43 of the rotary head 40 are yokes 55 serving as abutments for coil compression springs 56 interposed between said yokes and the blocks 50 and 51, the inner ends of the spring being received within the sockets 50a and 51a. The springs 56 thus tend to push the blocks inwardly toward each other. Said blocks 50 and 51 are furthermore formed adjacent the inner ends thereof, and adjacent the lower ends thereof with half-conical sockets or notches 50d and 51d, for the purpose hereinafter appearing.

Slidably mounted in openings 50b and 51b are vertical pins 58 and 59 countersunk on the undersides thereof to receive the upper ends of coil compression springs 58a and 59a interposed between said pins and the bottom ends of the openings 50b and 51b. Screwed to the pins 58 and 59 are horizontal guide pins 58b and 59b received within the vertical slots 50c and 51c. The pins 58 and 59 are thus urged upwardly by the springs 58a and 59a, but may reciprocate within their openings in the manner hereinafter appearing.

The upper ends 58c and 59c of the pins 58 and 59 are beveled in the same direction, so that the high points of said pins are in alignment. The wire W is fed between the pins 58 and 59, and twisted into zigzag shape upon oscillation of the rotary head 40, as will more fully appear hereinafter.

Means is provided to oscillate the rotary head 40. To this end, there is mounted on table 16, a vertical pivot pin 60, having a reduced portion 61 at its lower end passing through the opening 21. Fixed to the lower end of reduced portion 61 is a collar 62. At the upper end of pivot pin 60 is an enlarged flange 63. Rotatably mounted on pivot 60 is a gear 64 meshing with the gear 49.

Attached to the rear face of wall 17 are a pair of vertical plates 70 projecting above the table top 16. At the upper ends of plate 70 are horizontal aligned guides 71 open at the inner faces thereof, and slidably mounted within the guides 71 is a horizontal rack 72 having teeth on its inner face meshing with the gear 64. On table 16 are rotatably mounted a pair of idler pinions 73 disposed on opposite sides of gear 64 and meshing with the rack 72.

Rotatably mounted in the bearings 24 is a horizontal transverse shaft 75 carrying a gear 76 at its front end. The support 15 carries a bearing 77 disposed beneath the bearings 24 and supporting a shaft 78 on which is mounted a pinion 79 meshing with gear 76. On shaft 78 is a pulley 80 belted to an electric motor 81 mounted on the support 15.

It will now be understood that operation of motor 81 will cause rotation of shafts 78 and 75 through the meshing gears 79, 76.

On the rear end of shaft 75 is a rotary head 81a formed with parallel diametrical guides 82, on which there is slidably received a member 83. At one end of the guides 82, is a transverse wall 85, in which is rotatably and non-slidably mounted a screw 86 screwed into member 83.

It will now be understood that rotation of the screw 86 will cause sliding movement of member 83 relative to member 81a. Interconnecting a pivot pin 88 on member 83 with a pivot pin 89 on the rack 72, is a connecting rod 90a. It will now be understood that rotation of member 81a, which is fixed to shaft 75, will cause reciprocation of the rack 72, and hence oscillation of member 40. Furthermore, the extent of reciprocation of the rack may be adjusted by turning the screw 86. Thus, the adjustment of the screw 86 controls the angle of oscillation of the rotary head 40.

Means is provided to alternately depress the pins 58 and 59 after rotation of rotary head 40 in each direction, to permit the turns formed in the wire to pass off the pins, so that the zigzag shaped wire may be continuously formed. To this end, there is rotatably mounted within bearing 36 a shaft 90, to one end of which is fixed an arm 91 formed with a slot 92 and overlying the vertical opening 34 in wall 30 of the bracket 25.

Slidably mounted within opening 30 is a plunger 93, the upper end of which is slotted to receive arm 91, and provided with a transverse pivot pin 94 passing through the slot 92. Interposed between the upper enlarged end of plunger 93 and wall 30, is a coil compression spring 95 tending to raise the plunger. At the lower end of plunger 93 is a head 96 adapted to engage and depress pin 58 as rotary head 40 is rotated in one direction, and engage and depress pin 59, as said rotary head is rotated in an opposite direction.

Fixed to the opposite end of shaft 90 is an arm 100 provided with a pin 103 at the outer end thereof, parallel to shaft 90. In bearing 38 is a pivot pin 101 serving as a pivot for a lever 102. One end of lever 102 overlies pin 103. Attached to the opposite end of lever 102 is a member 104 having an inclined edge 105.

Fixed to shaft 75, and rotatable therewith, is a disc 110 formed with a pair of diametrically opposed arcuate slots 111. Through each of said slots is a bolt 112. The bolts 112 may be adjusted angularly within slots 111. Each bolt 112 has a head 113 adapted to be engaged by an inclined edge 105 of member 104 on the lever 102. Thus, during each revolution of disc 110, lever 102 is oscillated twice as member 104 is engaged by the heads 113 of bolts 112. Each time lever 102 is rotated in a counterclockwise direction, looking at Fig. 2 of the drawings, arm 100 is likewise swung downwardly in a counterclockwise direction to rotate shaft 90, to depress the plunger 93 to in turn depress one of the pins 58 or 59, whichever happens to be beneath the plunger.

Means is provided to arch the zigzag spring longitudinally as said spring is formed. To this end, there is mounted on the rotary head 40 a longitudinally curved guide 120. At the lower end of the guide 120 is a horizontal plate 120a, lying on top of the rotary head 40, and pivotally connected thereto by a vertical pivot pin 121. Guide 120 is in the form of a flattened tube or conduit and curves outwardly and upwardly, being open at both ends and of sufficient width to receive

the zigzag shaped spring formed from the wire W. The spring is longitudinally arched, as it passes through the guide 120. A plane passing through the pivot pin 121 and the axis of the rotary head 43, is at right angles to the plane passing through the pins 58 and 59 and the guide oscillates about the pivot pin during oscillation of the rotary head 40.

The formation of the U-turns or zigzag in the wire during operation of the machine will now be described:

As the wire passes between the pins 58 and 59, and rotary head 40 is rotated in one direction, the wire is bent into U-shape, and when fully bent, the pin 58 or 59 which is beneath the plunger is depressed, so as to pass beneath two arms of a U turn, and then the rotary head is rotated in an opposite direction, to twist the wire oppositely to form another bend and arm. Thus, a bend and an arm is formed each time the rotary head rotates in an opposite direction.

Beginning with the parts as shown in Fig. 18, it will be noted that the rotary head 40 has been rotated in a counterclockwise direction. Pin 58 is engaged within the U turn marked 130, and the pin 59 is engaged with a U turn marked 130a. As the pin 58 passes beneath plunger 93, lever 102 is rotated by disc 110 to depress the plunger, and head 96 thereof engages the beveled surface 58c of said pin to depress the pin and permit said pin to pass beneath the arms 131 and 132 to the position shown in Fig. 20, thus releasing the U turn 130. The rotary head 40 then rotates in a clockwise direction, thus forming another U-turn 133 having the arm 132 on one side thereof, and a newly formed arm 134 on the opposite side thereof. Pin 59 then passes beneath the plunger and is depressed to release said pin from U-turn 130a and arms 132, 134 as shown in Fig. 21 of the drawings. As the machine operates, wire is drawn through the passage 31, and the zigzag shaped wire which is formed passes into the chute or guide 120.

It will be noted that the spread of the arms of each U turn or the distances between said arms may be adjusted by regulating the bolts 112 on disc 110 within the arcuate slots 111. The position of these bolts control the timing of the release of pins 58, 59. By regulating such timing, the pins may be released somewhat sooner or later relative to the end of the oscillation of the rotary head 40. As the head approaches the end of each oscillation, the last U closes. By releasing the pin 58 or 59 a predetermined time in relation to the closing of this U, the width between the arms of the U may be regulated. Thus, if the last U is allowed to close more before the pin is released it will not open as much after the pin is released, as it would if the pin were released sooner. To explain, if a wire is bent into U shape, the more the arms are brought together, the less the arms will be opened up when released, and thus, the timing of the release of the pins 58 and 59 controls to a certain extent the degree of opening up of the U's and hence the distances between the arms of the U, and therefore also the lengths of the individual springs, as will appear more fully hereinafter.

The distances between the arms of each U turn may also be regulated by adjusting screw 86 which determines the length of reciprocation of the rack 72, and hence the angle of oscillation of rotary head 40. The greater the angle of rotation, the more the U turns will be closed, and hence the less the distances between the arms

of the U turns. If each spring has 18 turns, a slight increase in the distance between each turn increases the overall length of each spring.

Means is provided to gradually increase and then gradually decrease the widths of the U portions as well as the distances between the arms of the U turns every predetermined number of turns, so that the continuously formed zigzag spring may thereafter be cut into predetermined equal lengths by mechanism hereinafter to be described, each spring having turns decreasing in width and in distances between the arms of the turns from the outer ends toward the middle. To this end, there is rotatably mounted within the bearings 19 and 20, a horizontal transverse shaft 140 located beneath the table 16. On shaft 140 is a collar 141 contacting wall 18 of the support 15. On said shaft, furthermore, is a roller clutch 142 of well known construction, to permit shaft 140 to rotate in one direction only. Said shaft 140 carries an eccentric 143 located beneath the through opening 46. It will be noted that the axis of shaft 140 is in the plane of the axis of said opening 46.

Slidably mounted within opening 46 is a rod 145 having a conical or cammed upper end 146 received within the registering semi-conical openings 50d and 51d of the blocks 50, 51. The lower end of rod 145 contacts the bottom of the eccentric 143. On rod 145 is a fixed collar 148 and interposed between said collar and the lower end of sleeve portion 41 of rotary head 43 is a coil compression spring 149.

It will now be understood that as shaft 140 rotates, the eccentric 143 will raise rod 145 to separate the blocks 50 and 51. As the eccentric continues to rotate, spring 149 will lower the rod and springs 56 will move the blocks 50, 51 inwardly toward each other.

On shaft 140 is a ratchet 150 shown in the drawings for the purpose of illustration as having 18 teeth. Pivoted to shaft 140 is an arm 152 extending upwardly therefrom and interconnected by a coil tension spring 153, to plate 70, or some other fixed part of the support. On arm 152 is a pawl 154 engaging the teeth of the ratchet and retained against the ratchet by a tension spring 155 interconnecting said pawl with arm 152.

Means is provided for advancing the ratchet 150 through an angle equivalent to one tooth for each complete reciprocation of the rack 72. To this end, there is fixed to one end of said rack, a guide 160 carrying a rotatable and non-slidable longitudinal screw 161. Slidably mounted within the guide 160 is a member 162 having screw threaded engagement with the screw 161. Fixed to member 162 is a horizontal, longitudinal bar 164 carrying a roller 165 at the opposite end thereof lying in the path of arm 152. As the rack 72 moves from the right to the left, looking at Fig. 3 of the drawings, the roller 165 will engage the upper end of arm 152 to rotate ratchet 150 through an angle equivalent to one tooth of said ratchet. As the rack 72 moves from the left to the right, looking at Fig. 3, spring 153 will swing arm 152 in a clockwise direction, looking at Fig. 2 of the drawings, until said arm engages a fixed stop 166 adjustably fixed to the support 15. The screw 161 may be adjusted to insure rotation of arm 152 through a predetermined angle so that the ratchet 150 will be rotated through an angle of one tooth only during each reciprocation of the rack 72.

It will now be understood that there will be

18 reciprocations of the rack 72, and hence 18 oscillations of the rotary head 40 while the eccentric 143 makes one complete revolution, and hence while the rod 145 makes one complete reciprocation up and then down. It will be understood that said rod 145 moves upwardly and the blocks separate step by step, the width of the U turns will increase because the pins 58 and 59 will be spread apart. Increasing the width of the U turns will automatically increase the distances between the arms of the U turns. It will now be understood that every 18 U turns, the spring will repeat. During each repeat, the spring will decrease and then increase in width and in distances between the arms of the U portions, as illustrated in Fig. 23 of the drawings. By cutting the spring every 18th U turn, similar springs will be formed, as described hereinafter.

Bar 164 is formed with a slot through which the pivot pin 89 passes, as shown in Fig. 2 of the drawings.

It will be understood that if it is desired to produce springs having different number of turns, it is merely necessary to replace the 18th tooth ratchet 150 by a ratchet having a different number of teeth and then regulating the screw 161 to adjust the angle of rotation of the ratchet each reciprocation. Member 162 may be formed with markings 162a, and guide 160 may be provided with a pointer 160a cooperating with the markings 162a to indicate to what ratchet member 162 is set.

The spring advancing mechanism

As the spring is formed into zigzag shape, it passes to a spring advancing mechanism 170 synchronized with the spring making mechanism. To this end, there is fixed to the table 16 a pair of upright posts 171 located on opposite sides of the bracket 25. The posts 171 may be interconnected by a horizontal roller 172 located above said bracket. As the zigzag shaped formed spring passes out of chute or guide 120, it is passed upwardly over the roller 172 and then downwardly and to the right looking at Fig. 1 of the drawings. The table 16 is formed with a raised platform 16a and with a second raised platform 16b located at a level higher than the level 16a. On platform 16a are a pair of symmetrical guides 175 having horizontal, inwardly extending flanges 176. The inner edges of said flanges are spaced from one another, as shown in Fig. 3 of the drawings.

Slidably mounted on platform 16a and between the guides 175 is a block 177, the top surface of which is spaced below the undersurfaces of flanges 176. The zigzag shaped spring passes between the guides 175 and between the block 177 and the flanges 176, as illustrated in Figs. 10 and 11 of the drawings.

Block 177 is urged to the right looking at Fig. 3 of the drawings by a coil tension spring 171a, interconnecting said block with a pin fixed to the table 16. Screwed to said block, and extending longitudinally of the table, is a horizontal rod 180, the rear end of which slides within a sleeve 181 fixed to the table 16. On rod 180 are a pair of spaced collars 182 and 183.

Fixed to rack 72 is a transverse bar 185 adapted to engage collar 182. As rack 72 moves to the left, during each reciprocation, bar 185 will strike collar 182 and move block 177 to the left, tensioning the spring 171a. As the rack 72 again moves to the right, said spring will retract the block 177. Block 177 is formed with a longitu-

dinal slot 186, in which there is a transverse horizontal pivot pin 187. Pivoted thereon is a latch 188 having a downwardly projecting finger 188a at one end contacting the top of platform 16a, and an upwardly projecting finger 188b, at its opposite end, projecting above the top surface of block 177. The rear arm of the latch is heavier than the forward arm so that the finger 188b is normally maintained in a position shown in Fig. 10 of the drawings, projecting above the block.

It will now be understood that as the block 177 reciprocates, finger 188b will successively engage the arms of the U turns of the spring and advance the spring step by step through the guide 175. The spring is thus advanced through the guide in synchronism with the spring making mechanism.

Means is provided to prevent the spring from moving backwards within the guide. To this end, there is pivoted to said guide, a lever 190 normally urged downwardly by a spring 191 interconnecting the lever with some fixed part of the machine. Lever 190 has a finger 192 projecting downwardly between the flanges 176 and adapted to engage the arms of the spring. The spring may thus by-pass the finger 192 as it moves forwardly, but cannot move back due to engagement of finger 192 with the arms of said spring.

The cutting off mechanism

Means is provided to cut the zigzag spring fed past the guide 75 into similar equal lengths. To this end, there is fixed to table 16, adjacent one side of platform 16b, a frame or support 200 formed with a bearing 201 at the upper end thereof to support a transverse horizontal shaft 202 parallel to shaft 75. Fixed to the rear face of the support 200 are a pair of spaced, vertical guides 205 supporting therebetween a vertical slidable plate 205. Fixed to the lower end of plate 205 is a shear cutter 206. The face of the cutter is substantially in the plane of the front face of the platform 16b. Attached to said rear face of said platform is a hardened cutting block 16c which together with the cutter 206 forms a cutting shear. Attached to the platform 16b is an angular guide 207. The top surface of platform 16b is at the level of the top surface of block 177, so that the zigzag shaped spring passes from said block onto the top of the platform 16b, and beneath the guide 207. The width of platform 16b is less than the width of the U turns of the spring at the widest point in the spring, so that a portion of the spring projects beyond the block 16c and beneath the cutter 206, so that as the cutter comes down, as will be explained hereinafter, the bend 210 in the largest U of the spring will be cut off as indicated in Fig. 23 of the drawings, thus producing the last arm 12 of one spring and the first arm 12a of the next spring.

Shaft 202 is formed with an eccentric pin 212 journalled within the upper end of a crank 213 interconnected to the plate 205 by another plate 214.

It will now be understood that as the shaft 202 rotates, plate 205, and hence the cutter 206 will be reciprocated. The support 200 may be formed with a guide 215 to be contacted by the zigzag spring at the point of cut off, as illustrated in Fig. 6 of the drawings.

Means is provided to rotate the shaft 202 through one revolution to affect a cut off operation each time shaft 140 makes a complete revolution.

tion. To this end, there is mounted on and fixed to shaft 140, a disc 220 formed with a cam projection 221 in alignment with the high part of eccentric 143. Fixed to the underside of table 16 is a bracket 222 on which there is pivotally mounted a lever 223. The cam 221 is adapted to rotate the lever once during each revolution of shaft 140. Rotatably mounted on shaft 202 is a fly wheel 225 connected by belt 226 to a motor 227. When the machine is in operation, the motor operates continuously and the fly wheel 225 rotates continuously. The fly wheel 225 is operatively connected to the shaft 202 by one revolution clutch 228. Said clutch comprises a disc 229 mounted on and fixed to the shaft 202. Said disc is formed with a transverse opening 231 of rectangular cross-section. Slidably mounted within said opening is a slide bar 232, the outer face of which is formed with a slot 233 having an inclined face 234. The slide bar 232 is formed with a socket 236 in which there is slidably mounted a pin 237. A coil compression spring 238 in said socket normally presses the pin 237 against the support 200, thus tending to push the slide bar 232 against the adjacent face of the fly wheel 225. On said face of the fly wheel 225 is a pin 240, the same distance from the axis of the fly wheel as is slider bar 232.

Pivoted to the support 200 as at 243, is a latch 244 having a beveled outer edge 247 normally engaged within the slot 233, retaining the slide bar 232 to the left, as shown in Fig. 9 of the drawings, so that the fly wheel 225 can continuously rotate when rotating shaft 202 without pin 240 coming in contact with slider bar 232.

The latch 244 is interconnected to a lug 244a on the support 200, by a coil compression spring 244b to maintain said latch in engagement with the slider bar. Pivoted to support 200, as at 250, is a plate 251 interconnected to lever 223 by a connecting rod 223a. Plate 251 is formed with an opening 252 at an intermediate portion thereof. Pivoted to the latch 244 is a rod 255 passing through the opening 252. Fixed to the lower end of the rod 255 is a collar 256. Slidably mounted on said rod, and disposed below plate 251, is a sleeve 257. Interposed between the collar 256 and the sleeve 257, is a coil tension spring 260.

It will be noted that when the cam 221 strikes the lever 223, the lever will rotate in a clockwise direction, looking at Figs. 1 and 7, pulling down plate 251 and hence pulling the latch 244 out of slot 233, permitting spring 238 to move the slide bar 232 to the right, looking at Fig. 9 of the drawings, and into the path of the pin 240, so that when said pin contacts said slide bar, disc 229 which is fixed to the shaft 202, will be rotated to cause a shearing operation. When the disc 229 completes a revolution, latch 244 will again enter the slot 233 to pull the slide bar 232 again to the left, to stop rotation of the disc 229 and to disconnect said disc from the fly wheel which continues to rotate.

It will now be observed that the cut off mechanism operates in synchronization with the wire forming mechanism, so that the cut off will always be at the same sequence in the length of the spring, and each spring will have turns gradually decreasing in width from the outer ends toward the middle.

It will be further noted that the number of turns in each spring and the length of the spring may be varied without adjustment of the cut off mechanism.

Mechanism for supporting the springs during cut off and to pile the springs one on top of the other

It will be noted that a full length of spring passes beyond the cut off mechanism before the spring is cut off. Means is provided to support the length of spring which passes beyond the cut off mechanism prior to the cut off operation and to drop the cut off spring by gravity after each cut off operation, so that the springs will pile up, one on top of the other as they are cut off. To this end, there is fixed to the support 15, a pair of parallel, aligned, horizontal guide members 270 extending beyond the cut off and disposed longitudinally of the guide 75. Fixed to the guide plates 270 are plates 271 co-extensive with said guide plates, and extending inwardly therefrom, as illustrated in Figs. 14, 15 and 16 of the drawings. The guide plates 270 may be interconnected by transverse straps 272. Screwed to the undersides of said plates 270, are headed pins 274 supporting a pair of horizontal aligned plates 275 disposed on the undersides of plates 270, said pins 274 passing through slots 276 in the plates 275.

It will now be understood that the plates 275 may be slidably moved inwardly toward each other or outwardly away from each other. When the plates 275 are in the position shown in Figs. 14 and 15, the zigzag shaped spring passes between the guide plates 270 and is held in position by the bottom slideable guide plates 275 and the top fixed guide plates 271.

Means is provided to separate the plates 275 after each cut off operation to permit the cut off length of spring to drop downwardly to any suitable receptacle, so that said springs will pile up in such receptacle. To this end, there is fixed to the plate 270, a plurality of similar, symmetrically disposed brackets 277 rotatably supporting a pair of parallel rods or shafts 278 journaled within said brackets. Fixed to the forward ends of said shafts 278 are bars 280 and 281 interconnected by a sliding pivot connection 282 so that when the pivot is raised, the shafts 278 will be rotated inwardly, and when the pivot is lowered, said shafts will be rotated outwardly. Fixed to said shafts 278 are downwardly extending arms 285 slotted at their lower ends as at 286. Fixed to the undersides of plates 275 are brackets 287 carrying longitudinal rods 288 received within the slots 286.

It will now be understood that when the shafts 278 are rotated inwardly, the arms 285 will push the plates 275 inwardly toward each other, and when said shafts 278 are rotated outwardly, said arms will retract the plates 275 to permit the cut spring to drop as shown in Fig. 16 of the drawings.

Means is provided to normally lift the pivot 282 so as to move the guide plates 275 inwardly; and to lower said pivot after each cut off operation to permit the cut spring to drop. To this end, there is fixed to the plates 270 an overhead bracket 290 to which there is attached a Z-shaped arm 291. The upper end of arm 291 is interconnected by a coil tension spring 292 to the pivot 282, so as to normally raise the pivot. Mounted on the pin 282 is a pin 293 projecting through opening 294 in bracket 290.

Pivoted to the support 200, as at 295 is an arm 296 having one end overlying the pin 293. An adjustable screw 297 on arm 296 contacts the pin. On plate 214 is a roller 298 engaging the upper side of the lever 296 between the pivotal end 295 thereof and the outer end thereof. At each cut

off operation, plate 214 descends to swing the lever 298 downwardly and depress the pivot 282 to retract plates 275 and permit the cut spring to drop. After the cut off operation, spring 292 lifts the pivotal connection and also the arm 296.

It will be noted that each length of cut spring is longitudinally arched, being given such an arch by the curved guide 120.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described our invention, we claim as new and desire to secure by Letters Patent:

1. In a machine to make a zigzag shaped wire, in combination, a rotary member, a pair of parallel pins slidably mounted on said member on opposite sides of and parallel to the axis thereof, means to lead a wire between said pins, means to oscillate said member in opposite directions to form zigzag turns in said wire, and means to alternately depress said pins in synchronism with the oscillation of said rotary member.

2. In a machine to make a zigzag shaped wire, in combination, a rotary member, a pair of parallel pins slidably mounted on said member on opposite sides of and parallel to the axis thereof,

35 means to lead a wire between said pins, means to oscillate said member, means to alternately depress said pins in synchronism with the oscillation of said rotary member, and means to move the pins away from each other and then toward each other in increments, synchronized with the oscillation of said rotary member, to vary the width of the turns of the zigzag wire.

3. In a machine to make a zigzag shaped wire, in combination, a rotary member, a pair of parallel pins slidably mounted on said member on opposite sides of and parallel to the axis thereof,

45 means to lead a wire between said pins, means to oscillate said member, means to alternately depress said pins in synchronism with the oscillation of said rotary member, means to move the pins away from each other and then toward each other in increments, synchronized with the oscillation of said rotary member, to vary the width of the turns of the zigzag wire, and means to

50 oscillation of said rotary member, means to move the pins away from each other and then toward each other in increments, synchronized with the oscillation of said rotary member, to vary the width of the turns of the zigzag wire, and means to

55 adjust the timing of the depression of said pins relative to the oscillation of said rotary member.

4. In a machine to make a zigzag shaped wire, in combination, a rotary member, a pair of parallel pins slidably mounted on said member on opposite sides of and parallel to the axis thereof,

60 means to lead a wire between said pins, means to oscillate said member, means to alternately depress said pins in synchronism with the oscillation of said rotary member, means to move the pins away from each other and then toward each other in increments, synchronized with the oscillation of said rotary member, to vary the width of the turns of the zigzag wire, and means to

65 oscillation of said rotary member, means to move the pins away from each other and then toward each other in increments, synchronized with the oscillation of said rotary member, to vary the width of the turns of the zigzag wire, and means to

70 adjust the angle of oscillation of said rotary member.

5. In a machine to make a zigzag shaped wire, in combination, a rotary member, a pair of parallel pins slidably mounted on said member on opposite sides of and parallel to the axis thereof,

75 means to lead a wire between said pins, means

to oscillate said member, means to alternately depress said pins in synchronism with the oscillation of said rotary member, means to move the pins away from each other and then toward each other in increments, synchronized with the oscillation of said rotary member, to vary the width of the turns of the zigzag wire, means to adjust the timing of the depression of said pins relative to the oscillation of said rotary member, and means to adjust the angle of oscillation of said rotary member.

6. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, and means on said rotary member to arch the zigzag shaped wire longitudinally as said zigzag shaped wire is formed.

7. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, means to move the pins away from each other and then toward each other in increments, synchronized with the oscillation of said rotary member, to vary the width of the turns of the zigzag wire, and means on said rotary member to arch the zigzag shaped wire longitudinally as said zigzag shaped wire is formed.

8. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, and a longitudinally curved chute pivotally mounted on said rotary member adapted to receive the zigzag shaped wire as it is formed.

9. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, means to move the pins away from each other and then toward each other in increments, synchronized with the oscillation of said rotary member, to vary the width of the turns of the zigzag wire, and means synchronized with said means to move said pins apart to cut off predetermined lengths of said zigzag shaped wire.

10. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, and means, synchronized with said oscillating means, to advance said zigzag shaped wire past a point on the machine.

11. In a machine to make a zigzag shaped wire, 75 each other.

in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, means to move the pins away from each other and then toward each other in increments, synchronized with the oscillation of said rotary member, to vary the width of the turns of the zigzag wire, and means, synchronized with said oscillating means, to advance said zigzag shaped wire past a point on the machine.

12. In a machine for making a zigzag shaped wire, a pair of members to engage opposite sides of a wire, means to oscillate said members about an axis between said members in opposite directions to form zigzag turns in the wire, and means synchronized with said oscillating means, to disengage each turn in the wire from said members as the turn is made.

13. In a machine for making a zigzag shaped wire, means to engage opposite sides of a wire, 25 means to oscillate said first means to form turns in the wire, means synchronized with said oscillating means, to disengage each turn in the wire from said engaging means as the turn is made, a longitudinally curved chute receiving said zigzag shaped spring as it is made, and means to pivot said chute about an axis parallel to the axis of oscillation of said first means.

14. In a machine for making a zigzag shaped wire, a pair of members to engage opposite sides 35 of a wire, means to oscillate said members about an axis between said members to form turns in the wire, means synchronized with said oscillating means, to disengage each turn in the wire from said members, as the turn is made, and means to adjust the distance between said members to increase the width of the turns made in the wire.

15. In a machine for making a zigzag shaped wire, means to engage opposite sides of a wire, 45 means to oscillate said first means in opposite directions to form zigzag turns in the wire, means synchronized with said oscillating means, to disengage each zigzag turn in the wire as the wire is made, and means synchronized with said oscillating means, to cut off predetermined lengths of the zigzag shaped wire.

16. In a machine for making a zigzag shaped wire, means to engage opposite sides of a wire, means to oscillate said first means to form turns 55 in the wire, means synchronized with said oscillating means, to disengage each turn in the wire as the wire is made, means synchronized with said oscillating means, to cut off predetermined lengths of the zigzag shaped wire, means to receive and support each length of wire before it is cut off, and means controlled by the cut off means to release the cut off lengths of wire to permit the same to drop by gravity.

17. In a machine of the character described, an oscillating member, means to oscillate said member, a pair of blocks slidably mounted on said member for movement toward and away from the axis of said member, means to bias said blocks toward each other, parallel pins slidably mounted on said blocks, for longitudinal movement parallel to the axis of said member, means to bias said pins in one direction, means to alternately move said pins in the opposite direction, and means to move said blocks way from

18. In combination, a member adapted to oscillate about its axis, a pair of depressible spring pressed means slidably mounted on opposite sides of the axis of said member in directions, parallel to said axis, means to lead a wire between said pair of means, means to oscillate said member whereby to twist said wire into zigzag shape, means to alternately depress said pair of means, to disengage said zigzag wire as it is formed, and means to longitudinally arch said zigzag shaped wire as it is formed.

19. In combination, means to alternately twist a wire in opposite directions to form a zigzag shaped wire, means controlled by first means, to longitudinally arch said wire, and means synchronized with the first means, to cut off predetermined lengths of said wire.

20. In combination, means to alternately twist a wire in opposite directions, to form a zigzag shaped wire, means to longitudinally arch said wire, means to cut off predetermined lengths of said wire, means to support the cut off lengths of said wire, and means to release said supporting means to permit said cut off lengths to drop by gravity.

21. In combination, means to alternately twist a wire in opposite directions to form a zigzag shaped wire, means to longitudinally arch said wire, means to cut off predetermined lengths of said wire, and means to adjust the first means to successively increase the widths of a predetermined number of turns and then successively decrease the widths of a number of turns.

22. In combination, means to alternately twist a wire in opposite directions to form a zigzag shaped wire, means to longitudinally arch said wire, means to cut off predetermined lengths of said wire, means to adjust the first means to successively increase the widths of a predetermined number of turns and then successively decrease the widths of a number of turns, and means to vary the number of turns which increase in width and the number of turns which decrease in width.

23. In combination, a member adapted to oscillate about an axis, a pair of aligned blocks slidably mounted on said member and movable toward and away from each other, springs to urge said blocks toward each other, a pair of pins parallel to said axis mounted on said blocks for reciprocation, springs to urge said pins in one direction, a pin having a cammed portion between said blocks adapted to spread said blocks when moved in one direction, spring means to move said last pin in the opposite direction, a shaft, a cam on said shaft adapted to engage said last pin and move the same in said first direction, upon rotating said shaft, a ratchet on

said shaft, means to oscillate said member, and means controlled by said oscillating means, to advance said ratchet step by step in synchronization with the oscillation of said member.

5 24. In combination, a member adapted to oscillate about an axis, a pair of aligned blocks slidably mounted on said member and movable toward and away from each other, springs to urge said blocks toward each other, a pair of pins parallel to said axis mounted on said blocks for reciprocation, springs to urge said pins in one direction, a pin having a cammed portion between said blocks adapted to spread said blocks when moved in one direction, spring means to move said pin in the opposite direction, a shaft, a cam on said shaft adapted to engage said last pin and move the same in said first direction, upon rotating said shaft, a ratchet on said shaft, means to oscillate said member, means controlled by said oscillating means, to advance said ratchet step by step in synchronization with the oscillation of said member, a plunger adapted to depress said pair of pins, and means synchronized with said oscillating means, to cause said plunger 20 to alternately depress said pins adjacent the ends of the oscillations of said member.

25. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, and means to 30 adjust the timing of the depression of said pins relative to the oscillation of said rotary member.

26. In a machine to make a zigzag shaped wire, in combination, a rotary member, a pair of parallel pins slidably mounted on said member on opposite sides of and parallel to the axis thereof, means to lead a wire between said pins, means to oscillate said member, means to alternately depress said pins in synchronism with the oscillation of said rotary member, and means to 40 adjust the angle of oscillation of said rotary member.

27. In a machine for making a zigzag shaped wire, pairs of members to engage opposite sides of a wire, means to oscillate said members about an axis between said members, to form turns in the wire, means synchronized with said oscillating means, to disengage each turn in the wire from said members, as the turn is made, and means to adjust the timing of said disengaging 50 means.

ALBERT M. BANK.
ALEXANDER NICHOLAS.
